CLAIM

The ornamental design for a memorabilia ball simulacrum, as shown and described.

DESCRIPTION

FIG. 1 is a perspective view of a memorabilia ball simulacrum;

FIG. 2 is a front view of the memorabilia ball simulacrum;

FIG. 3 is a rear view of the memorabilia ball simulacrum;

FIG. 4 is a side view of the memorabilia ball simulacrum;

FIG. 5 is a bottom view of the memorabilia ball simulacrum; and,

FIG. 6 is a perspective view of the memorabilia ball simulacrum in a stand.

The broken lines in FIGS. 1, 2, and 6 representing an autograph, and in FIG. 6 representing a stand show environment, and form no part of the claimed design.

1 Claim, 5 Drawing Sheets(56)
